COMBINED TRANSISTOR-INTEGRATED CIRCUIT TESTER AND DESIGN AID

Joseph Don Jack, 314 Warren St.,
Harrison, N.J. 07029

Filed Sept. 28, 1973, Ser. No. 401,595

Term of patent 7 years

Int. Cl. D10—05

U.S. Cl. D10—75

FIG. 1

FIG. 2

FIG. 1 is a front elevational view of a combined transistor-integrated circuit tester and design aid showing my new design;

FIG. 2 is a right side elevational view thereof, the left side being substantially a mirror image thereto;

The top, bottom and rear of the claimed design are substantially plain and unornamented.

I claim:

The ornamental design for a combined transistor-integrated circuit tester and design aid, as shown and described.
